UNITED STATES PATENT OFFICE.

CHARLES M. KING, OF WASHINGTON, DISTRICT OF COLUMBIA, ASSIGNOR TO A. G. SPALDING & BROS., OF NEW YORK, N. Y., A CORPORATION OF NEW JERSEY.

BASE-BALL GLOVE AND MITT.

1,072,012.

Specification of Letters Patent. Patented Sept. 2, 1913.

Application filed August 8, 1912. Serial No. 714,066.

To all whom it may concern:

Be it known that I, CHARLES M. KING, a citizen of the United States, residing at Washington, in the District of Columbia, have invented new and useful Improvements 5 in Base-Ball Gloves and Mitts, of which the following is a specification.

My invention relates to base ball gloves or mitts, and pertains more particularly to 10 the class of such articles in which the front and back portions thereof are separably united and between which padding material is carried and separably secured to said front and back portions to permit of the adjustment of the thickness and location of the 15 padding.

The object of my invention is to produce a base ball glove or mitt of said class which is provided with a ring or heel of padding 20 material carried upon the main body portion of the padding material to which access may be readily had for adjustment to conform to the individual preferences of the users.

A further object thereof is to produce a 25 separable ring or heel for the padding of gloves or mitts of said character comprising a casing carried upon the face and adjacent to the outer edge of the main body portion of the padding material and provided with 30 eyelets adjacent to its outer edge adapted to be laced together for convenient opening to provide access to permit of the adjustment of the padding material contained therein, and a still further object of my invention is 35 to produce a more simple, cheap and efficient article of said class than has heretofore been provided.

To these ends my invention includes the 40 combination and arrangement of component parts to be hereinafter described and more particularly pointed out in the claims.

In the accompanying drawing in which like reference characters indicate similar parts, Figure 1 is a perspective view of the 45 padding of a base ball mitt of my invention with the outer covers removed; Fig. 2 is a longitudinal sectional view of the same with the front and back portions thereon, and Fig. 3 is a perspective view of my invention

applied to the padding structure of a finger 50 glove.

Referring to the drawing, 1 indicates the palm or face portion of the base ball glove or mitt of my invention, and 2 the back portions which are separably united to each 55 other, either entirely or partially around their outer edges by the eyelets 3 and lacing 4 and with which these parts are separably united to the blank 5 on which the main body portion 6 of the padding mate- 60 rial is secured through the eyelet 7 adjacent to the outer edge of the blank.

In the structure thus described it will be appreciated that access may be readily had to the main body portion of the padding material and that same may be modified and adjusted and secured in position upon the blank 5, but in gloves or mitts as heretofore constructed no provision has been made for the adjustment of the padding material contained in the ring or heel 8 carried upon the face of the main body portion 6 to enable the user to renew or adjust the same according to his preference and the condition of wear. For this purpose I construct the cas- 70 ing 9 open around its outer edge and provide a row of eyelets adjacent to the outer edge of the upper and lower walls which may be secured together and closed by the cord end laced through the said eyelets. By 75 such a construction it will be apparent that the location and amount of contents of the padding material 11 carried in said casing may be readily modified and regulated.

Having thus described my invention, what 80 I claim as new and desire to be secured by Letters Patent, is—

1. A pad for base ball mitts or gloves, comprising a main body portion and a split-ring of padding material carried upon the 90 face of said main body portion adjacent to the outer edge thereof, said split-ring comprising a case of flexible fabric having an opening therein and adapted to be stuffed with padding material, and means for clos- 95 ing said opening.

2. In a pad for base ball mitts or gloves, the combination with a blank of flexible ma-

terial adapted to be removably secured to the outer edges of the cover of the glove, of a main body portion of padding material secured on said blank, a case of flexible material having an opening therein adapted to be stuffed with padding material, means for closing said opening in the case, said case being carried on the face of said main body

portion of padding material conforming to the outer edge thereof, substantially as described.

CHARLES M. KING.
